CLAIM

The ornamental design for a bottle retaining device, as shown and described.

DESCRIPTION

FIG. 1 is a perspective view of a bottle retaining device; FIG. 2 is a right side elevation view of the bottle retaining device;

FIG. 3 is a left side elevation view of the bottle retaining device;

FIG. 4 is a front elevation view of the bottle retaining device;

FIG. 5 is a rear elevation view of the bottle retaining device;

FIG. 6 is a top elevation plan view of the bottle retaining device; and,

FIG. 7 is a bottom elevation plan view of the bottle retaining device.

The shade lines and dotted areas in the Figures show contour and not surface ornamentation.

The broken lines and the areas within the bounds of the broken lines depict portions of the bottle retaining device that form no part of the claimed design.

The appearance of any portion of the article between symbolic break lines forms no part of the claimed design.

1 Claim, 5 Drawing Sheets
